UNITED STATES PATENT OFFICE.

COLVIN L. JOHNSON, OF ST. LOUIS, MISSOURI, ASSIGNOR TO JOHNSON AUTOMOBILE LOCK CO., OF ST. LOUIS, MISSOURI, A CORPORATION OF MISSOURI.

GEAR-SHIFT-LEVER LOCK.

Original application filed February 28, 1927, Serial No. 171,448. Divided and this application filed September 19, 1927. Serial No. 220,590.

The present invention relates in general to lever locking mechanism, and more particularly to a mechanism which may be effectively employed to contemporaneously lock a gear shift lever in an inoperative position and for breaking the automobile engine ignition circuit. The present application is a division of my co-pending patent application, Serial No. 171,448, filed February 28th, 1927.

An object of my invention is the provision of lever locking mechanism of the above type wherein the control means for operating the locking mechanism forms a part of the lever handle and is slidable on the lever.

Another object of the invention is the provision of a locking device of the above described character wherein both the locking and unlocking operations may be effected by a movement of the slidable lock housing at the handle end of the shift lever.

Still another object of my invention is to provide a lever locking device embodying interiorly releasable means for locking a cover over the pivot of the lever.

A further object of the invention relates to the provision of a gear shift lever lock which is simple, durable and relatively inexpensive to manufacture and which may be conveniently locked and unlocked by the manipulation of the lever handle.

Still a further object of this invention resides in the provision of novel means operable by the locking mechanism for the gear shift lever to open a switch disposed in the automobile engine ignition circuit.

Other objects and advantages of my invention will more fully appear from the following detailed description, taken in connection with the accompanying drawings, which illustrate a single embodiment thereof and in which:

Figure 1 is a fragmentary elevation of a gear shift lever handle embodying lock mechanism of my invention;

Figure 2 is a fragmentary vertical sectional view through the lever;

Figure 3 is an enlarged fragmentary vertical section taken through the lever handle

and locking mechanism associated therewith with parts shown in elevation;

Figure 4 is a fragmentary sectional view taken on the line IV—IV of Figure 3 looking in the direction indicated by the arrows and showing the handle in a locked position;

Figure 5 is a fragmentary sectional view similar to Figure 4 illustrating the handle in its unlocked position;

Figure 6 is a sectional view taken on the line VI—VI of Figure 2 and illustrating the construction of the lever;

Figure 7 is an enlarged fragmentary side elevation with parts in section illustrating the locking mechanism in combination with an ignition control switch, and

Figure 8 is an enlarged fragmentary detail section illustrating the ignition switch in Figure 7 in open position.

In the drawings:

Like reference characters designate similar parts throughout the several views. The reference numeral 1 indicates a gear shift lever which is pivotally mounted in a transmission housing cover 2 on the usual ball 3, the ball ordinarily being secured to the lever by a pin 4. The ball 3 and the lever 1 are secured from longitudinal movement relative to the cover 2 by means of a locking wire 5 inserted in the groove in the wall of the cover portion directly above said ball.

Undesirable vibration of the lever in its pivotal mounting is prevented by a gasket or washer 6 which is secured in the recess in the cover 2 directly above the ball 3 and the wire 5. Access to the pivotal mounting of the lever is prevented by a cover member 7 which has a concave under surface 8 and which is lockingly secured to the lever by a spring-pressed internal plunger 9 which engages in a recess in said lever. The plunger 9 is in practice released by pushing a tool or rod upwardly through groove 21 in the lever alongside of the rod 22.

The upper end of the lever 1 is provided with a slightly enlarged portion 1^a which is recessed at its upper end as at 1^b, and slidably mounted on said enlarged portion 1^a is a cylindrical casing 10 which has secured

thereto an annular member 11 with a spherical surface whereby the casing 10 and said member 11 afford a substantially ball-shaped handle for the lever 1. Mounted in the upper end of the casing 10 with its outer end flush with the upper end of said casing is a lock cylinder 12 which is provided at its inner end with a plug 13 rotatable relative thereto through the insertion of a suitable key in the cylinder, said plug 13 in turn being provided with an eccentric projection 14 which acts when the lock cylinder is rotated to withdraw a lock bolt 15 from a recess 15^a formed in the inner wall of the casing 10. Said lock bolt 15 is slidably mounted in a lateral recess in the enlarged portion 1^a of the lever 1 and is normally urged outwardly relative to the surface of said enlarged portion 1^a by means of a helical spring 16 which is engaged between the end of the recess and a shoulder 17 formed on said bolt 15. The bolt 15 is reduced in diameter between said shoulder 17 and its outer end to afford a recess for the reception of the eccentric projection 14, said eccentric projection 14 contacting that face of the shoulder 17 opposite the end of the spring 16 when the plug 13 is rotated to retract the bolt 15.

30 The casing 10 and the mechanism carried thereby are normally urged upwardly by a helical spring 18 engaged in the recess 1^b between the inner end of the cylinder 12 and the end of the lever portion 1^a at the bottom of said recess 1^b. When the plug 13 is rotated to retract the lock bolt 15, the spring 18 will force the casing 10 and the parts carried thereby upwardly into the position shown in Figure 5 at which time the bolt 15 will snap into a recess 19 and retain the casing 10 in said position shown in Figure 5 which will be noted hereinafter as unlocked position. This retaining of the casing 10 in unlocked position prevents accidental downward movement of said casing during normal manipulation of the lever and when it is desired to push the casing 10 downwardly into the position shown in Figure 4, it is only necessary for the operator

40 to press inwardly on the laterally extending button 20 which is reciprocably mounted in the casing 10 and the end of which communicates with the recess 19. This pressure on the button 20 will push the bolt 15 out of the recess 19 and will permit the casing to be pushed downwardly by the application of pressure to the end of the handle portion.

45 The reciprocable movement of the handle portion on the end of the lever 1 controls a mechanism for locking said lever from operation in a manner which will now be described. Said lever 1 is provided with a longitudinal passage 21 (Figure 6) in which a wire connecting rod or link 22 is reciprocably mounted. The upper end of the wire

22 terminates in a lateral portion 22^a which extends into an elongated recess 23' formed in the enlarged portion 1^a at the end of the lever 1. Permanently secured in the casing 10, and extending into said recess 23' is a blind stud or set screw 24 into which the lateral portion 22^a of the connecting rod or wire 22 extends and is secured.

The passage 21 through the lever is preferably formed by milling a groove in said lever and then closing the outer end of said groove by the insertion of a wire 21^a and welding compound 21^b therein, after which the outer surface of the lever is smoothed and buffed to provide virtually an integral construction with the interior passage 21. That portion of the groove formed in the lever below the cover member 7, however, in the present instance, is preferably not closed so that that portion of the passage 21 below said cover member 7 is in effect only a groove in the lever which is clearly shown in Figure 2 and which I have designated by the reference numeral 21^c.

The connecting rod or wire 22 is provided at its lower end with a lateral projection 22^b which is connected to a sleeve or collar 23 slidably mounted on the lower extremity of the lever 1 and adapted to engage when in its lowermost position in an aperture 24' defined by bosses 25'-25' formed integral with the transmission housing cover 2 to lock the lever from operation when the lever is in a neutral position, as is well known in the art. It will thus be apparent that when the casing 10 and the parts carried thereby are in the position shown in Figure 5, it is only necessary for the operator to press inwardly on the button 20 and downwardly on the handle portion afforded by said parts to force the locking sleeve or collar 23 downwardly until the bolt 15 snaps into the recess 15^a and locks said handle portion in the position shown in Figure 5. This downward movement of the handle portion will, of course, serve to move the sleeve or collar 23 downwardly into locking engagement in the manner previously referred to.

It will be apparent from the foregoing description that I have provided a lever locking mechanism which may be conveniently and effectively used to lock levers such as automobile gear shifting levers and the like from unauthorized operation. The mechanism which I have provided is very easy and convenient to lock and unlock being only necessary to push the release button 20 and press downwardly on the handle to effect the locking operation and being only necessary to insert a key in the lock cylinder and rotate the same thereby to permit the unlocking operation to automatically take place. By reason of the construction which I have provided, it is possible to retain the desired neat appearance and small dimensions of a usual

gear shift lever and at the same time have the lever equipped with the improved locking mechanism of my invention.

In Figures 7 and 8 I have shown a lever locking mechanism embodying the principles of the present invention used in conjunction with an ignition control switch in such a manner that a movement of the handle casing to locking position serves to automatically 5 open the ignition circuit and stop the automobile engine. By virtue of this construction, those instances wherein the owner forgets to lock the automobile are greatly minimized, since the most convenient way to stop 10 the engine when leaving the automobile is to push down the handle casing and lock the gear shift lever. The construction whereby this dual result is accomplished comprises the mounting of switch control means in the 15 path of the locking sleeve 23 which, as previously described, is slidably mounted on the lower portion of the lever 1 and which is controlled by the movement of the handle casing 10 and the handle 11 in the manner previously 20 described. The lever is locked from movement through the engagement of the sleeve or collar 23 in the opening formed between the two bosses 25'-25'.

In order to facilitate the actuation of the 30 ignition switch by the downward movement of said sleeve or collar 23 to locking position, I preferably chamfer the lower edge of said sleeve or collar, as indicated at 39°. Slidably and adjustably mounted in a passage 35 through one of the bosses 25' is a plunger 41, the inner end of which is rounded and normally projects into the opening between the bosses 25' in the path of the sleeve or collar 23. The adjustable mounting for the plunger 40 41 is secured through a threaded plug 42 which engages in the threaded recess in the outside of the transmission housing cover 2 and the outer end of which is abutted by the integral shoulder 41a formed on said plunger. 45 The outer end of the plunger 41 is secured to a flat leaf spring member 43 one end of which is secured to a stud 44 projecting from the transmission housing cover. The leaf spring 43 is insulated from said stud 44 and 50 the plunger 41 is in turn insulated from the leaf spring by suitable insulating washers. Also secured to the stud 44 and insulated therefrom is a leaf spring 45 similar in construction to the leaf spring 43 and spaced 55 therefrom. The leaf spring 45 is provided with an opening 46 through which the enlarged portion 41a of the plunger 41 extends without contacting said leaf spring 45.

The springs 43 and 45 respectively carry 60 contact members 47 and 48 which are normally held in contact by the resiliency of the spring 43. The springs 43 and 45 are also electrically connected in the ignition circuit of the automobile engine on which the transmission 65 embodying my locking mechanism is

mounted through suitable electrical conductors 49 connected thereto and extending outwardly through an opening in a flange 50 which is preferably integral with the transmission housing cover and which encloses the 70 switch mechanism just described. By virtue of the construction described herein, the contacts 47 and 48 are normally together thus completing the ignition circuit, but when said contacts are forced apart by the engagement 75 of the sleeve or collar 23 with the plunger 41 when said sleeve or collar is moved to locking position, the ignition circuit is opened and the engine is stopped.

While the entire control of the ignition 80 circuit is normally effected through the locking and unlocking of the lever locking mechanism of this invention, I have also found it desirable in certain instances to provide a "coasting switch" whereby the ignition circuit may be disconnected without locking the gear shift lever. This may conveniently be accomplished by forming the ends of the springs 43 and 45 in the manner shown in the drawings at 51 and providing 85 an auxiliary switch operator for insertion between the springs at this point to force the same and the contacts 47 and 48 apart. The auxiliary switch operator which I have provided for this purpose comprises a 90 plunger 52 which is slidably mounted in the casing 53 and which is normally spring retracted by a helical spring 54 mounted in said casing. The casing 53 is mounted in a flange 50' formed integral with housing 2. 100 Also it will be noted that the two flanges are connected by a detachable cover or closure plate 51'. The lower or inner end of the plunger 52 is preferably constructed of insulating material, as shown at 55, and is 105 adapted to engage the formed ends of the springs 43 and 45 to hold the same apart in the manner indicated in Figure 8. The engagement of the portion 55 with the formed ends 51 of the springs is in a manner similar 110 to that common in telephone jack construction, the frictional engagement between said parts being sufficient to hold the plunger in position to separate the springs until the same is manually released and allowed to 115 move back to the position shown in Figure 7 under the impetus of the spring 54. The plunger 52 is preferably provided with a button shaped exterior portion 56 for engagement by the hand or foot of the operator. As previously noted, this auxiliary switch operator mechanism is not normally used but is provided to meet those contingencies wherein it is desired to shut off the 120 engine without locking the gear shift lever. Normal control of the ignition system for starting and stopping the engine is effected through the locking and unlocking operations previously described herein.

Now, of course, it is to be understood that 130

although I have illustrated and described my invention in detail, the invention is not to be thus limited, but only in so far as defined by the scope and spirit of the appended claims.

I claim as my invention:

1. The combination with a gear shift lever of a housing therefor, a locking member slidably connected to said lever, lock means connected to the upper portion of said lever to control the operation of said locking member, means projecting inwardly from said housing and defining an opening through which said lever extends and into which said locking member is movable to lock the lever against operation, a plunger extending into said opening and operable by the movement of said locking member into said opening, and an ignition switch associated with and operable by said plunger.
2. The combination with a gear shift lever of a housing therefor, a locking member slidably disposed on said lever, means movable on the handle end of said lever for operating said locking member, means connected to said housing defining an opening

through which said lever extends and into which said locking member is arranged to be moved to lock the lever against operation, and a switch associated with said latter means and including an element projecting into said opening for engagement by said locking member when said locking member is moved into said opening whereby said switch is operated contemporaneously with the locking of said lever against operation.

3. In a switch associated with a transmission housing and controlled by a gear shift lever locking means operated by the handle member of the lever, cooperable switch contact members, means for controlling the operation of said members extending inwardly into said housing and into an opening formed in said housing to receive said lever locking means when said lever is locked against operation, said latter switch means being so positioned as to open said switch when the lever is locked against operation.

In testimony whereof I have hereunto subscribed my name.

COLVIN L. JOHNSON.
